DENTURE ANCHOR

Louis Glenn Cody, Denver, Colo.

Application January 29, 1942, Serial No. 428,681

7 Claims. (Cl. 32—6)

This invention relates to improvements in means for holding partial dentures in place.

As is well known to those skilled in the art, a bridge, plate, or partial denture, including one or more false teeth, is commonly installed in the mouth by dentists to take the place of missing teeth when less than a complete denture or set of false teeth is required. Ordinarily, such partial dentures are fastened to natural teeth either permanently or removably. There is a serious objection to such an anchorage, however, because some of the forces involved in biting or chewing on the partial denture are usually transmitted to the natural tooth or teeth that provide the anchorage. These forces and stresses tend to loosen the natural tooth or teeth thus acted upon, as is well understood by the dental profession. Obviously, this is undesirable.

Therefore, it is a principal object of the present invention to provide means whereby such a partial denture may be removably, yet dependably, positioned in the mouth and fastened to one or more natural teeth in a way that will not transmit damaging forces or stresses to such natural teeth.

Another object is to provide such means in convenient form for manufacture, distribution, and use by the dental profession.

A further object is to provide such means that are entirely dependable and satisfactory from the viewpoint of the person in whose mouth it is installed.

Other objects and advantages reside in details of design and components, which will become manifest as this disclosure progresses.

In order to disclose an operative reduction to practice of the present inventive concept, the accompanying drawing will be described in some particularity. The drawing is more or less diagrammatic and is drawn to a greatly exaggerated scale for purposes of clearly setting forth the advanced principles that comprise the invention.

In the drawing,

Figure 1 is a plan view partially in section and drawn to an enlarged scale, indicating a device that embodies the present invention;

Figure 2 is an end elevation thereof as indicated by arrow 2 of Figure 1;

Figure 3 is a longitudinal central section as indicated by line 3—3 of Figure 1; and

Figure 4 is a sectional view as indicated by the line 4—4 of Figure 3.

Reference character 15 denotes a socket-forming downwardly tapered sleeve that is to be cast into a gold inlay, which in turn is mounted in the

natural tooth that is to provide anchorage for the partial denture. A retention sleeve 16 is made of a size and shape to slide into the socket-forming sleeve 15 in removable wedge-like engagement therewith.

The socket-forming sleeve 15 is vertically open along its side adjacent which opening are guides 15a which cooperate with the retention sleeve 16 to hold the latter in place. If the retention sleeve 16 tends to have or to acquire a loose fit in the socket from wear and usage, then the guide-contacting parts 16a of sleeve 16 can be bent to grip the guides 15a more securely, to provide a clasp effect.

Within the retention sleeve 16 and partly extending therefrom is a slide or breaker bar 17, which is slidable up and down therein and with reference thereto within limits provided by the folded-over closures 18 and 19.

The slideable breaker bar 17 preferably is made of one piece folded upon itself to provide resilient wings 20 and 21, each of which is notched to form locking tongues 22 and 23 respectively. The outer edges of the wings 20 and 21 converge downwardly and terminate in tips 24 and 25 respectively.

A tailpiece 26 terminates in a locking slide 27 that is positioned at substantially right angles to said tailpiece and is adapted by its size and shape to fit snugly over locking wings 20 and 21 and be locked thereon by tongues 22 and 23.

The denture ordinarily comprising one or more false teeth is mounted upon the universal tailpiece 26, which tailpiece is of a size and shape to be cut and fitted to the job at hand by the dentist. Its cross-like shape provides for both left or right side dentures.

The fastening of the tailpiece 26 by means of its integral locking slide 27 to the locking wings 20 and 21 is semi-permanent and is intended for convenient assembly by the dentist. It is entirely possible for the dentist in the course of his professional work to remove the tailpiece 26 and its locking slide 27 from the wings 20 and 21 when the occasion arises. In this way, the assembly readily can be serviced by the dentist without laboratory expense.

The various components herein illustrated and described are intended to be made of stainless sheet metal such as alloy steel or the like, that possesses the desirable properties of strength, malleability, and resistance to corrosion.

It is manifest that the various components that comprise these advanced means for holding a partial denture in place, are highly important

articles of manufacture, which can be produced economically in quantity and distributed to the dental profession. Dentists using these components readily can adapt them to the job at hand and assemble them into their final relationship as herein illustrated and described. Such means are highly advantageous to the dental practitioner and to the patient in whose mouth they are used.

In use, the socket-forming sleeve 15 is cast into a gold inlay or the like, which in turn is mounted in the natural tooth of the patient. The denture is prepared and mounted on the tailpiece 26 as will be understood by those skilled in the art, which in turn is locked semi-permanently onto the slide or breaker bar 17, by means of locking tongues 22 and 23. This slide or breaker bar 17 is slidably enclosed within the retention sleeve 16, after which the denture assembly is ready to be mounted in the mouth of the patient.

The retention sleeve 16 is finally slipped into the socket-forming sleeve 15 in the natural tooth, thus providing a removable yet dependable anchorage for the denture to the natural tooth. It is to be understood that this same mounting can be provided at both ends of the denture if desired, by duplicating the parts herein illustrated and described.

The denture is designed to bear upon the natural gum of the wearer, and as the forces of biting or chewing are borne by the denture it can slide up and down within limits, thus preventing the transmission of any detrimental forces to the natural tooth or teeth to which the assembly is fastened.

The relationship of the retaining sleeve 16 to the socket 15 is a wedge-like engagement which securely holds the denture and yet provides for complete removal of the entire denture assembly at will.

The principle involved in this invention is known as broken stress, because detrimental forces and stresses are not transmitted to the natural teeth and yet a definite occlusal stop is provided, with controlled movement in all directions.

The gum of the wearer provides part of the occlusal stop, but after the gum has compressed the amount of the movement of the slide 17, then the natural tooth provides some of the stop, but since the stress is broken within the vertical axis of the natural tooth, there will be no lever arm of force acting on said tooth.

Because of the features herein set forth, no great amount of precision of installation is required so the present denture anchor is unusually easy to install, and satisfactory to wear.

What I claim and desire to secure by Letters Patent is:

1. A device of the character described, comprising a socket-forming sleeve adapted by its size and shape to be attached to a natural tooth, a retention element of corresponding size and shape fitted for limited vertical movement in said socket-forming sleeve in wedge-like engagement therewith, a resilient breaker slide retained in said retention element for limited universal movement relative thereto and having a portion projecting horizontally therefrom, and a denture-supporting tailpiece attached to the projecting portion of said breaker slide for limited independent vertical movement, whereby forces exerted vertically against the tailpiece in a user's mouth cannot transmit leverage against the tooth on which said sleeve is mounted.

2. A device of the character described, comprising a tapered socket-forming sleeve adapted by its size and shape to be attached to a natural tooth, a retention element of corresponding size and shape fitted for limited vertical movement in said socket-forming sleeve in wedge-like engagement therewith, a resilient breaker slide retained in said retention element for limited universal movement relative thereto and having a portion projecting horizontally therefrom, and a denture-supporting tailpiece attached to the projecting portion of said breaker slide for limited independent vertical movement, whereby forces exerted vertically against the tailpiece in a user's mouth cannot transmit leverage against the tooth on which said sleeve is mounted.

3. A device of the character described, comprising a socket-forming sleeve adapted by its size and shape to be attached to a natural tooth, a retention element of corresponding size and shape fitted for limited vertical movement in said socket-forming sleeve in wedge-like engagement therewith, a resilient breaker slide retained in said retention element for limited universal movement relative thereto and having a portion projecting horizontally therefrom, a denture-supporting tailpiece attached to the projecting portion of said breaker slide for limited independent vertical movement, and means on said projecting portion for locking said tailpiece thereon whereby forces exerted vertically against the tailpiece in a user's mouth cannot transmit leverage against the tooth on which said sleeve is mounted.

4. A device of the character described, comprising a socket-forming sleeve adapted by its size and shape to be attached to a natural tooth, a retention element of corresponding size and shape fitted for limited vertical movement in said socket-forming sleeve in wedge-like engagement therewith, a resilient breaker slide retained in said retention element for limited universal movement relative thereto and having a portion projecting horizontally therefrom, means for retaining said slide in said element, and a denture-supporting tailpiece attached to the projecting portion of said breaker slide for limited independent vertical movement, whereby forces exerted vertically against the tailpiece in a user's mouth cannot transmit leverage against the tooth on which said sleeve is mounted.

5. A device of the character described, comprising a socket-forming sleeve adapted by its size and shape to be attached to a natural tooth, a retention element of corresponding size and shape fitted for limited vertical movement in said socket-forming sleeve in wedge-like engagement therewith, a resilient breaker slide retained in said retention element for limited universal movement relative thereto and having a portion projecting therefrom and terminating in locking wings, and a denture-supporting tailpiece attached to the projecting portion of said breaker slide by means of said wings, whereby forces exerted vertically against the tailpiece in a user's mouth cannot transmit leverage against the tooth on which said sleeve is mounted.

6. As an article of manufacture, a dental device of the character described, comprising an open-side socket-forming sleeve adapted by its size and shape to be fixed on a natural tooth, a resilient breaker slide constructed and arranged to fit in said sleeve for limited universal movement relative thereto and having a portion projecting horizontally therefrom, means for limiting the universal movement of said breaker slide,

and a denture tailpiece having means for its attachment to the projecting portion of said breaker slide permitting limited independent movement whereby forces exerted vertically against the tailpiece in a user's mouth cannot transmit leverage against the tooth on which said sleeve is mounted.

7. As an article of manufacture, a dental device of the character described, comprising an open-side socket-forming sleeve adapted by its size and shape to be fixed on a natural tooth and having guides adjacent and parallel to the opening, a resilient retention element of a size and shape to fit slidably in the socket in wedge-like

5 engagement therewith and having guide-contacting portions, a breaker slide constructed and arranged to fit in said retention element for limited universal movement relative thereto and having a portion projecting horizontally therefrom, and a denture tailpiece having means for its attachment to the projecting portion of said breaker slide permitting limited independent movement, whereby forces exerted vertically against the tailpiece in a user's mouth cannot transmit leverage against the tooth on which said sleeve is mounted.
